UNITED STATES PATENT OFFICE.

WILLIAM ROSE, OF GAINSBOROUGH, ENGLAND.

APPARATUS FOR APPLYING BANDS, WRAPPERS, OR LABELS TO BOXES, BLOCKS, OR PACKAGES.

1,111,676.

Specification of Letters Patent. Patented Sept. 22, 1914.

Application filed June 29, 1910. Serial No. 569,562.

To all whom it may concern:

Be it known that I, WILLIAM ROSE, a subject of the King of Great Britain and Ireland, of Albion Works, Gainsborough, in the county of Lincoln, England, have invented new and useful Improvements in Apparatus for Applying Bands, Wrappers, or Labels to Boxes, Blocks, or Packages, of which the following is a specification.

This invention has for its object to provide simple and efficient apparatus by which bands, wrappers, or labels, can be rapidly and accurately applied to boxes, blocks, or packages. For brevity, the articles to which the bands, wrappers, or labels, are to be applied are hereinafter referred to as "packages," and the bands, wrappers, or labels, are referred to as "paper bands."

The apparatus according to this invention comprises means for the supply of paper bands; a device which moves in one direction and takes up adhesive, and then, by means of this adhesive, takes up a paper band and moves in the reverse direction and conveys the said band to, and deposits it on, a table with an opening therein corresponding to the length and breadth of the packages to be dealt with; a device for receiving and carrying the packages and depositing them upon the paper band placed over the opening in the table aforesaid, and for pressing the said paper band and package into a receiver beneath; devices to fold each end of the paper band over the package, when so required; a retainer, the cross-sectional area of which is equal to the length and breadth of the packages, so as to assist in shaping them; and an ejector for expelling the packages into a trough, where they remain the required time to allow the adhesive to dry. The apparatus also comprises modified means, by which the paper bands are held upon the table and wrapped around the boxes, blocks, or packages, and it also consists in the use of means whereby the interior of the magazine can be adjusted to adapt it to any irregularities in the paper band as regards cutting, or printing, for example, and so as to minimize the risk of taking up more than one paper band at a time. The devices for holding one end of the paper band and for turning it over by means of a pinion and toothed sector and for pressing and smoothing it down may be like those hereinafter described, but the part of the

table which is at the other end of the paper bands and capable of tilting and advancing over the packages to lay the short end of the paper band upon the package may be provided such as hereinafter more fully described, with a second gripper which grips that end of the paper band while it is gripped at the other end by the first named gripper, and means are provided whereby a small movement is given to the part of the table carrying the second gripper so that the paper band is stretched taut just before, and while, the package is placed on the band on the table. The apparatus also comprises modified mechanism for conveying the packages to over the paper band on the opening in the table; means for exerting additional pressure on the packages in the receiver when a package is being forced into the aforesaid receiver; means for more efficiently supplying adhesive to the device which applies the adhesive to the paper bands; mechanism which will permit of lengthwise-rocking movement of the adhesive-applying device, in order to permit of the said device accommodating itself to any slight inequalities in taking up adhesive; means for preventing injury to the packages and means for properly retaining the folds or tabs in position on the ends of the packages; a modified form of receiver into which the packages are delivered; and means which will insure the paper band being kept in position sidewise during folding.

I will particularly describe my invention with reference to the accompanying drawings, in which—

Figures 1 and 2 show opposite side elevations, Figs. 3 and 4 end elevations looking in the direction of the arrows A and B, respectively, of Fig. 1 and Fig. 5, in plan, a general arrangement of the apparatus as constructed in accordance with my invention. The remaining figures are detail views, drawn to a larger scale, of parts, or modifications of the said apparatus. Referring to these details, Fig. 6 shows, in elevation, the package magazine, the operating cams and levers, and other associated parts. Figs. 7, 8, 9 and 10 illustrate, in four positions, the means for applying adhesive to the top paper band in the machine, removing the said paper band from the magazine and carrying it to and depositing it on the part of the machine where it is to be ap-

plied to the package. Fig. 11 is an elevation and Fig. 12 is a plan showing the mechanism for operating the device which takes up a supply of adhesive, applies it to, and 5 picks up the top paper band in the magazine and delivers it to a position to receive a package, the said views showing also the mechanism for operating the device which pushes the paper off the aforesaid device. 10 Figs. 13, 14 and 15, illustrate the package carrier mechanism in three positions, and the plunger. Figs. 16 and 17, illustrate the means for operating the said carrier mechanism and the plunger. Figs. 18, 19, 20, 21, 22 15 and 23 illustrate six positions of the folding devices, Fig. 18 illustrating operating mechanism in connection therewith and also the receiver for the wrapped packages. Figs. 24, 25 and 26 are views at right angles of that 20 part of the table which supports the long end of the upper band, showing also the gripper carried thereby. Fig. 27 is a section on the line α — α of Fig. 26. Fig. 29 is an elevation. Figs. 28 and 30 are views at right angles thereto, Fig. 31 is a plan, and Fig. 32 is a 25 horizontal section, taken on the line y — y of Fig. 29, of the receiver for the wrapped packages. Figs. 33, 34, 35, 36 and 37 illustrate five other positions of the folding devices. Fig. 38 shows in side elevation, Fig. 39 in front elevation, Fig. 40 in side elevation, opposite to that shown in Fig. 38 with part broken away, and Fig. 41 in plan, the magazine provided with means to adjust the 35 interior thereof to adapt it to the irregularities of the paper bands. Fig. 41^a is an elevation of the magazine provided with a device to signal when the supply of paper bands therein becomes exhausted, and Fig. 40 40 in side elevation partially in section showing a locking device actuated by the magazine and preventing the operation of the machine so long as the magazine is out of feed position. Figs. 42 and 43 are a side 45 and end elevation respectively of the improved package-carrier mechanism. Fig. 44 is a side elevation (partly in section) of the improved mechanism which exerts additional pressure on the packages in the receiver. Figs. 45 and 46 show two different 50 positions of the fixed surface 19. Figs. 47 and 48 are end and side elevations respectively of the adhesive-applying device, Fig. 49 being a plan of Fig. 47. Figs. 50, 51 and 55 55 52 are respectively an end elevation, a side elevation, and plan, all drawn to a larger scale, of the mechanism for adjusting the lever which carries the adhesive-supplying device. Fig. 53 is a front elevation, Fig. 54 60 a plan, and Fig. 55 a side elevation of the mechanism which permits of lengthwise-rocking of the adhesive-applying surface. Figs. 56 and 57 show in end elevation and plan, the mechanism which prevents the 65 packages being injured during ejection of

the said packages from the feeding trough. Fig. 58 shows in end elevation the mechanism by means of which the packages are taken up and transferred to the paper bands. Figs. 59 and 60 are elevations of the mechanism as viewed from opposite sides of Fig. 58, and Fig. 61 is a plan of Fig. 58. Figs. 62 and 63 are a side elevation, and plan respectively of the improved receiver for the wrapped packages. Fig. 64 is a side elevation, 75 and Fig. 65 a plan of the tilting tables and their actuating mechanism for folding the band or wrapper on the package; Figs. 66 and 67 are plan and elevation respectively of one of the tilting tables and its 80 gripper drawn to a larger scale.

The device 11, see Figs. 7, 8, 9, 10, 11, and 12, which takes a supply of adhesive from the roller 23 and is brought over the magazine 1 to take up the top paper band and convey it to the table where it is to be applied to the package, is connected to, or integral with, a sleeve 18, mounted on a shaft 19 carried by side arms 62, connected by a bridge-piece 262 and mounted on a shaft 61; the said arms 62 operate to cause the device 11 to rock the required distance between the magazine 1 and the table where the paper band is deposited and is applied to the package. An arm 263 on the sleeve 18 carries the pin, or stud, 20, pivotally connected, by the link 22, with the arm 21 to which motion is imparted so as to raise and lower the device 11 at the required times in order to cause the device 11 to take a supply of adhesive from the adhesive-supplying roller 23 (or part of a roller) dipping into and revolving in the container 24, carrying the adhesive, and then, when in position over the top paper band in the magazine 1, to cause 100 the device to descend and pick up the said paper band and carry it (free of contact with the adhesive-supplying roller 23) and deposit it on the table over the opening 105 therein. The device 11 for receiving and applying the adhesive and carrying the paper band, has an underside 25 corresponding in shape to the paper bands but preferably a little less in area than the paper band, so that there is no danger of the adhesive extending over the edge of the paper band. If the adhesive be only required to be applied in patches, then grooves, or recesses, 110 63 (see Fig. 4) may be formed in the said underside 25 of the device 11 in the places 115 where the adhesive is not to be applied, and, to insure the paper band being deposited over the opening in the table, I provide a device 26 operated in the said, or special, 120 grooves, or recesses, in the said underside 25 125 to push off the paper band. This device is integral with, or carried on, arms 64 of a bridge-piece 264, mounted on the shaft 19, on one of the bosses of which there is an arm 265 connected by a link 65, and an arm 130

66, to the shaft 61 to which the side arms 62 carrying the sleeve 18 are connected.

The aforesaid levers 62, 21, and 66, are caused to be actuated as shown in Figs. 11 and 12 in the following manner:—Mounted on suitable extensions on one of the side levers 62 are anti-friction rollers 68 and 69 with which engage co-acting cams 70 and 71 respectively, mounted on the main driving shaft 60 of the machine. The cam 70 acts upon the roller 68 to cause the device 11 to move from the adhesive-supplying roller 23, as shown in Fig. 7, to a position above the magazine 38, as shown in Fig. 8; a cam 74, secured to the main driving shaft 60, acts upon an anti-friction roller 75 to cause the sleeve 18 to rock on the shaft 19 to cause the device 11 to descend upon the pile of paper bands in the magazine to pick up the top paper band, as shown in Fig. 9, the cam 71 then acting to cause the device 11 to carry the paper band to a position to receive the package. A cam 72 secured to the main shaft 60 acts upon an anti-friction roller 73 to cause the arm 66, to which the device 26 is connected, to move with the device 11, but will prevent the said device from coming into contact with the adhesive supplying roller 23, as shown in Fig. 7, but when the said paper band is brought to the aforesaid position to receive the package will act to cause the device 26 to push the paper band off the device 11 onto the said table and hold it thereon while the device 11 is rising, the said cam 72 then permitting the device 26 to rise and return to the adhesive-supplying roller 23. The adhesive supplying roller may be caused to rotate in the container 24 of adhesive in any convenient manner. In Fig. 2 this is shown as being effected by means of a belt 170 and pulleys 171 and 172, the pulley 171 being secured to the main driving shaft 60 and the pulley 172 being secured on a shaft 173 carried by the frame of the machine. To the shaft 173 is secured a spur wheel 174 (see Fig. 6) which transmits rotary motion therefrom to the shaft 175 of the adhesive-supplying roller through a spur wheel (not shown) on the said shaft 175. A jockey pulley may be employed (as shown at 176 in Fig. 2) to keep the said belt 170 taut.

The packages to which the paper bands are to be applied may be fed as usual along a trough (see Figs. 1, 2, and 5) having an endless chain, or belt, 29, passing along the bottom of the said trough and having either continuous, or intermittent, movements imparted to it, an obstacle 30 (Fig. 5) however being placed at the end of the trough to intercept the end package, so that a plunger 31 (see Fig. 5) acting transversely to the said belt can push the end package onto a platform 32 (see Figs. 13, 14, and 15), which can be brought over the opening

in the table on which the paper band is deposited and between the jaws 34 and 35 of a carrier 33, the said movable platform 32 being supported and operated so that when the jaws of the carrier 33 have gripped the package, the said platform 32 moves out of the way to allow the jaws 34 and 35 to carry the package downward onto the deposited paper band. The jaw 34 may be fixed to the carrier, the other jaw 35 being hinged and closed by a spring 107 and caused to open by an extension 36 thereon coming in contact with the aforesaid movable platform 32 to allow the package to be pushed, by the plunger 31, into correct position between the jaws 34 and 35. Fig. 13 shows the movable platform 32 with a package thereon acting upon the extension 36 to open the hinged jaw 35. Fig. 14 shows the package gripped between the jaws 34 and 35, and Fig. 15 is a similar view to Fig. 14, but showing the movable platform retiring. Mounted in the package carrier 33, so as to be slidable therein, is a plunger 37, which is caused to push the package from between the jaws of the carrier 33 and, together with the paper band, through the opening in the table into a receiver 38 (see Fig. 18), the paper band being thereby folded over the ends of the package.

The plunger 31 may be caused to reciprocate in any suitable manner, preferably as indicated in Figs. 1, 3, 4, and 5, wherein is shown a spring 108 acting, through a lever 109, to rock a shaft 110, to which is secured a lever 111 connected, by a link 112, to the plunger 31, to push the package onto the movable platform 32, a face cam 113 acting on an arm 114 integral with the aforesaid lever 111 to return the said plunger. The said plunger is suitably mounted and guided on a rod 115 carried by the main frame of the machine.

The movable platform 32 is caused to be operated by a cam 80 secured to the main driving shaft 60, see Figs. 2, 3, 4, and 5, which, through an anti-friction roller 81, actuates an arm 82 secured to a shaft 83, the said shaft 83 having also secured thereto, or integral therewith, a lever 84 carrying the said movable platform 32.

The carrier 33 may descend by gravity, or by the action of a spring, and it is caused to be raised by a cam 85 (see Figs. 16—17) on the main driving shaft 60 acting, through an antifriction roller 86, on an arm 87 secured to a sleeve 88 on a shaft 89, the said sleeve 88 being connected by a bridge-piece 90 to another sleeve 91 carrying the arm 33. The antifriction roller 86 may be kept in engagement with the cam 85 either by gravity, or by the action of a spring. The plunger 37 is caused to descend and ascend in unison with the aforesaid carrier 33 by coacting cams 92 and 93 (see Figs. 16—17) secured to the main driving shaft 60, which act upon

levers 94 and 95, through antifriction rollers 96 and 97 respectively, the former cam 92 acting to cause the plunger 37 to ascend and the latter cam 93 causing it to descend. The levers 94 and 95 may be integral, constituting a bell-crank lever, or, as shown, they may be separate levers having thereon projections 98 and 99, respectively, which are normally held together by a spring 100, the 10 said spring permitting of the levers yielding if required. In the figures referred to, the lever 94 is shown integral with a sleeve 101 connected by a bridge-piece 102 to a sleeve 103 carrying the arm 104 to which arm the plunger 37 is connected by a link 105, and the lever 95 is shown integral with a sleeve 106 freely mounted on the shaft 89.

When it is required to fold the paper band over the fourth side, or top, of the package, preferably so that the ends of the paper band overlap each other, the table which receives the paper band may be provided with parts 39 and 40 (see Fig. 18) which act as folders. For this purpose 25 the part 39 of the said table is supported and pivoted on an arm of a bell-crank lever 41, and is capable of tilting on a pivot 42 and of advancing over the package so as to turn down the short end 43 of the paper band upon the package. The said part 39 of the table is caused to tilt by a cam 116, see Figs. 3 and 4, secured to the main driving shaft 60 of the machine, which, through an antifriction roller 117, acts, in 30 opposition to a spring, upon an arm 118 on a sleeve 119 on a shaft 120, the said sleeve 119 being connected by a bridge-piece 121 to another sleeve 122, also on the said shaft 120, the latter sleeve 122 having integral therewith an arm 123 connected by a universal joint 124 to a rod 125 pivotally connected at its upper end to the outer end of the table 39. The said table is caused to advance as aforesaid by a cam 126 secured to 35 the main driving shaft 60 of the machine, which through an antifriction roller 127 acts in opposition to a spring upon an arm 128 on a sleeve 129 on the shaft 120, the said sleeve having integral therewith an arm 130 connected by a rod 131 to an arm of the bell-crank lever 41 pivotally mounted on the frame of the machine. The part 40 of the table at the opposite end of the opening therein is connected to an arm 44 and the 40 said part 40 is provided with a gripper 46 for holding (under the action of a spring 47) the long end 48 of the paper band, and the said part 40 is caused, when the package and paper band are being pressed through 45 the opening to move a distance about equal to the thickness of the packages operated upon so as to hold the end 48 of the paper band and follow up the package as it descends. The said part 40 is caused to be 50 moved as described, by a cam 140 (see Figs.

3 and 4) secured to the main driving shaft 60 of the machine, which, through an anti-friction roller 141, acts, in opposition to a spring, upon an arm 143 integral with a sleeve 144 on the shaft 120; secured to, or 55 integral with, the said sleeve 144 is an arm 145 connected by a rod 146 to an arm of a bell-crank lever 147 pivoted at 148 to the frame of the machine, the upper part 44 of the other arm of the said bell-crank lever 147 carrying a pinion, or toothed sector, 54, hereinafter referred to.

The gripper 46 is held open when the paper band is being deposited on the table by a roller 49 on an arm 50 connected with 60 the gripper 46 coming in contact with a movable stop 51, and, on the return movement of the movable stop 51, after the paper band has been deposited, the gripper 46 returns, under the action of its spring 47, and 65 grips the end of the paper band. The movable stop 51 is operated by a cam 149 (see Figs. 3 and 4) secured to the main driving shaft 60 of the machine, which, through an anti-friction roller 150, acts, in 70 opposition to a spring upon an arm 152 integral with a sleeve 153 on the shaft 120; secured to, or integral with, the said sleeve 153 is an arm 154, connected, by a universal joint 155, to a rod 156, the upper end of the 75 said rod 156 being connected to an arm of a bell-crank lever 157, pivoted to the main frame of the machine, the upper part of the other arm of the said bell-crank lever constituting the movable stop 51. When the 80 upper side of the package is about on a level with the top of the table, and after the movable part 39 of the table at the other end of the opening has turned down the short end 43 of the paper band at that end, the movable part 40 of the table carrying the gripper 46 turns over and carries the long end 48 of the paper band over and onto the upper face of the package and is then 85 drawn along so as to pull the said paper band taut, to draw the gripper away from the long end thereof and also to smooth and press the paper band down onto the packages. The aforesaid actions may be effected by the pinion, or toothed sector, 54, before 90 referred to, secured to the axis 45 of the folder 40 carrying the gripper 46, the center of the said pinion, or toothed sector, 54 being about level with the top of the package when depressed to a level with the table, the face of the folder 40 being on a line 95 with the axis 45 of the said pinion, or sector, 54, which pinion, or sector, engages with a toothed sector, or rack, 55 actuated so as to cause the aforesaid part 40 carrying the 100 gripper 46 to operate as described.

The toothed sector, or rack, 55, is operated by a cam 158 (see Figs. 3 and 4) secured to the main driving shaft 60 of the machine which, through an antifriction 105

roller 159, acts, in opposition to a spring, upon an arm 161 integral with a sleeve 162 on the shaft 120, the said sleeve 162 having secured thereto, or integral therewith, an arm 163, connected, by a rod 164, to an arm of a bell-crank lever 165 pivoted at 148 to the frame of the machine, the other arm of the said bell-crank lever carrying or having integral therewith, the before mentioned 10 rack 55.

Fig. 18 shows the table, which is comprised of the part 39, the top of the preceding package in the receptacle 38 and the part 40, in readiness to receive a paper band, 15 the gripper 46 being held open by the movable stop 51. Fig. 19 shows the part 40 advancing toward the receptacle 38 and turning on its pivot, 45, to permit of the package being forced into the receptacle 38 20 without the long end of the paper band being withdrawn from the gripper 46. Fig. 20 shows the paper band and the package forced into the receptacle and the folder 39 tilted and advanced to fold the short end 25 of the paper band over the package and the part 40 in further advanced and turned position than that shown in Fig. 19. Fig. 21 shows the folder 39 in its retired position having previously folded over the short end 30 of the paper band, and the part 40 in a still further advanced and now completely turned position. Fig. 22 shows the part 40 in its completely advanced position having smoothed and pressed down the long end of 35 the paper band onto the package, and Fig. 23 shows the said part retiring.

In order to prevent the gripper 46 from damaging the package, while smoothing and pressing down the long end of the 40 paper band, a part 240 of the folder 40 is recessed or beveled as shown in Figs. 24, 25, 26, and 27, to permit of the gripper 46 being above the acting surface of the folder when in the position shown in Fig. 21.

45 The packages with the bands applied which have been passed through the opening in the table are held up by a spring device 56 (see Figs. 6, 18, 28, 29, 30, 31, and 32) pressing on the side of the lowermost package, which device, when the next package is forced in, will yield and allow the lowermost package to fall clear of the rest into a position to be expelled by a plunger 57 (see Fig. 6) into the trough 58, through which 55 the packages pass to be held till the adhesive is sufficiently dry. The plunger 57 is secured to or integral with, an arm 257 secured to a shaft 284, see Figs. 2, 3, 4, and 6, the said shaft 284 being caused to rock to 60 operate the plunger by means of a sector arm 282 secured to the rocking shaft 88 to which the movable platform 32 is connected as hereinbefore described, the said sector arm 282 gearing with another sector arm 283 secured to the said shaft 284.

Referring now to the folding and gripping devices and the various mechanisms illustrated in Figs. 33 to 41, both inclusive, it will be seen that the second gripper 1^a is operated by being hinged to the part of 70 the table 39 to which it is applied and connected with the part 51, which acts as the movable stop for the first gripper 46, so that this connection causes the two grippers 46 and 1^a to act simultaneously. This connection may be a connecting bar 2^a attached at one end to the bell-crank lever 157, which carries the movable stop 51 and at the other end to a lever 3^a, pivoted at 4^a to the frame 75 of the machine against which lever 3^a the tail 5^a of the second gripper 1^a bears under the action of a spring 6^a. After the part of the table 39 carrying the second gripper 1^a, has tilted up, advanced, and folded over the short end 43 of the paper band over the 80 package, the second gripper 1^a being released, the said part 39 of the table returns and the long end 48 of the paper band is folded over the package as hereinbefore described. The before mentioned connecting 85 bar 2^a may carry a projection 7^a by which one end wall 8^a of the receptacle 38 through which the packages pass, may be caused to move outward slightly to allow the package to pass easily through the opening. This 90 wall 8^a is for this purpose carried by a lever 9^a centered at 10^a and kept normally closed by a spring 11^a, the bell-crank lever 157 being actuated by its cam at the proper time to move the connecting bar 2^a so that the 100 said wall 8^a is moved outward to the required extent by the projection 7^a on the connecting bar 2^a coming in contact with the projection 12^a on the lever 9^a. The paper band may be stretched taut just before, and while the package is placed on the said paper band on the table by a slight backward movement of the end 39 of the table, which 105 can be effected at the proper time by a suitable formation of a part of the cam that actuates the lever 41 hereinbefore referred to. In order to give an indication when the paper bands in the magazine 1 are exhausted, or about to become exhausted, the movable bottom 2 of the magazine 1 is provided with a projection 15^a which actuates a lever 16^a so as to bring a spring lever, or catch, 17^a pivoted to an arm 18^a into the path of a movable part 19^a of the machine, the said lever or catch 17^a carrying a hammer 20^a or the like, which is then caused to 115 strike a gong, or bell 21^a or actuate other suitable signaling device. The lever 16^a and the arm 18^a, are preferably integral and are mounted on a stud 22^a carried by the 120 frame of the machine, or they may be connected in any convenient manner which will permit of their moving in unison. 125

The operation of the arrangement shown in Fig. 41^a is as follows:—When the movable 130

bottom 2 of the magazine 1 has reached a predetermined height the projection 15^a thereon engages the lever 16^a and by the further ascent of the movable bottom 5 the said projection raises the lever 16^a and the arm 18^a whereby the spring lever, or catch, 17^a, is brought into the path of the movable part 19^a, which part as it descends acts on the said spring lever, or catch, 17^a, to raise 10 the hammer 20^a in opposition to the action of a spring 23^a. The movable part 19^a subsequently (as it commences to ascend) releases the said spring lever, or catch, 17^a, whereupon the hammer, under the action of 15 the spring 23^a strikes the gong, or bell 21^a. The movable part 19^a can be conveniently carried by the arm 82 in connection with the removable platform for receiving and carrying the packages to the opening in the table 20 on which the paper band is deposited, the said arm being operated by the cam 80 through the antifriction roller 81 as hereinbefore described.

In order to prevent the apparatus being 25 put into operation while the magazine for the paper bands is out of its position for feeding paper bands to the apparatus, I provide in connection with the magazine, means, described hereafter, whereby when it is 30 swung out of its feeding position, for charging it with paper bands, or for other purpose, a device is actuated which will obstruct the means by which the apparatus is started, the said device moving, or being moved, out 35 of its obstructing position when the magazine is swung back into its proper feeding position. The arrangement for this purpose is shown in Fig. 41^b, and consists of a shaft 2^b carrying a counter-weighted lever 40 3^b, a crank-arm 4^b and a cam 5^b, the counter-weighted lever 3^b being for conveniently giving motion of partial rotation to the shaft 2^b by throwing over the said lever, so that, through a link 6^b connecting the crank-arm 45 4^b with the magazine 1^b, the magazine is readily swung into, and out of, its feeding position, and the cam 5^b being so arranged that when the magazine 1^b is turned out of its feeding position, the said cam 5^b will act 50 upon one arm 7^b of a lever, the other arm 8^b of which has an end 9^b adapted to engage with a groove 10^b between a boss on the frame and the rear end of the sliding member 11^b on the shaft 120^b, which sliding member 55 has to be moved longitudinally on the shaft 120^b to start the apparatus. When the magazine 1^b is returned to its feeding position, the end 9^b of the said lever will, by falling by gravity, or otherwise, become disengaged from the said groove 10^b, or between the boss and the sliding member 11^b, and allow the starting of the apparatus 60 to be effected.

The mechanism shown in Figs. 42 and 43 65 inclusive relates to the carrier and the mov-

able platform by which the packages are conveyed to over the paper band on the opening in the table. Instead of making the jaw which is farthest from the movable platform 32^b in the direction in which it moves toward the carrier movable, as hereinbefore described, and the other jaw fixed, the jaw 35^b which is first in the direction of movement of the platform is made movable and the other jaw 34^b fixed, the movable jaw being hinged to the body part of the carrier 33^b from which projects a bracket 31^b carrying a three-armed lever 12^b, or a shaft provided with three arms, one arm 13^b being connected, by a spring 14^b, to the bracket 31^b, the second arm 15^b being in the path of a projection 16^b from the lever 84^b which carries the platform 32^b and the third arm 17^b being connected by a link, or links, 18^b with the movable jaw 35^b. When the projection 16^b on the platform lever 84^b acts on the second arm 15^b, the arms are turned so that the movable jaw 35^b is opened against the action of the spring 14^b and when the platform 32^b retires, the spring 14^b returns the jaw 35^b to its closed position, in which position it is retained by the link 18^b, or links, which are prevented from over-riding this position by stops, such as shown, the said link or links, coming in line, or about in line, with the center of the three-armed lever 12^b, or of the shaft carrying the three arms, so that the link 18^b, or links, will act as a strut to keep the jaw 35^b securely closed, while the plunger 37^b acts to press the package down onto the platform 32^b to shape it while in the top position and to subsequently force the package down from the jaws 34^b, 35^b, and onto the paper band, and, with the said band, through the opening on the table 95 beneath and into the receiver.

In order to exert an additional¹ pressure on the packages in the receiver 38^b when the plunger 37^b is forcing in a package and paper band, the arrangement shown in Figs. 110 44, 45 and 46 is used, wherein the surface 19^b upon which the lowermost package descends from the receiver 38^b, is carried by a lever actuated so that, as the said plunger 37^b is acting downward, the surface 19^b upon 115 which the lowermost package bears is raised so that the packages in the receiver 38^b are pressed between the said surface and the plunger 37^b. As some packages are very springy, there is a tendency of the packages to expand after pressure has been applied by means of the aforesaid plunger and surface 19^b, and because of this, the said surface 19^b is moved downward before the plunger 37^b is removed, which allows of expansion of the packages taking place only 120 downwardly. Fig. 45 shows the surface 19^b in that position which it assumes by reason of the expansion of the packages, in which position the surface 19^b remains until the 125

5 folding is completed, and Fig. 46 shows the surface still further lowered and the package in position to be ejected from the said surface. The arrangement for this purpose preferably consists of a bell-crank lever 20^b carrying at the end of one arm 23^b the said surface 19^b, and connected to one arm 24^b of a lever centered to any suitable fixed part, the other arm 25^b of which last named lever 10 is acted upon by a spring 26^b and is connected by a rod 27^b with another bell-crank lever 28^b acted upon by a cam 29^b. The other arm 30^b of the bell-crank lever 20^b is connected by a link 31^b with a fixed center 36^b so that the surface 19^b, against which the lowermost package bears, has a motion such that it maintains a horizontal position when in action.

15 Referring now to Figs. 47 to 59, both inclusive, these views illustrate a modified form of the adhesive-supplying mechanism, the object of which is to supply adhesive in a more efficient manner to the device by which the adhesive is transferred to the 20 paper bands, and by which the said paper bands are carried forward to the portion of the machine where they are to be applied to the packages. When the paper bands are of considerable width, and the adhesive 25 has therefore to be transferred to some considerable extent thereof, as the said adhesive-transferring and taking-up device must have a flat surface in order to properly take up the band, the device which supplies the adhesive to the said flat surface is liable 30 not to come properly in contact with the whole of the necessary portions of the said flat surface, and therefore not to efficiently supply adhesive in the required quantity 35 thereto. The device which supplies adhesive to the said flat surface is mounted and operated so that it will have such movement as will cause it to follow the movement of the said flat surface and to properly supply adhesive thereto. The adhesive-supplying device 23^c (consisting, for example, of a trough and roller), is carried by a lever 2^c fixed 40 upon a shaft 3^c, to which is also fixed an arm 4^c operated, preferably by a roller and 45 cam arrangement against the action of a spring from the rotating shaft 60^c which drives the machine, so that the said device 23^c is tilted in such a way as to follow, and 50 keep in contact with, the aforesaid flat surface 12^c as it moves thereover, such movement of the flat surface being hereinbefore 55 described. In order to adjust the lever 2^c which carries the said adhesive-supplying device, the said lever 2^c is loose on the shaft, 60 and the said shaft 3^c has fixed to it an arm 4^c connected by a bridge piece to the projecting part 5^c which extends between forks 1^c formed on the rear end of the lever 2^c which carries the adhesive-supplying device, 65 so as to allow of some play between this

projecting part 5^c and the bifurcations 1^c, 1^c of the said fork. One bifurcation of the fork is provided with a spring 6^c pressing on the projecting part 5^c so as to force it against an adjusting screw 7^c passed through 70 the other bifurcation of the fork, by adjusting which screw the position of the adhesive-supplying device is regulated. The said screw can be retained in its adjusted position by any suitable device, such for 75 instance, as a screw, or spring-catch, 8^c adapted to engage in one, or other, of a series of notches 9^c formed on the upper surface of the lever 2^c.

80 The mechanism as shown in Figs. 53, 54 and 55 allows of the aforesaid flat surface 12^c having a sufficient capacity for rocking movement lengthwise to accommodate it to any slight inequalities in taking up adhesive and also in applying itself to the 85 paper bands in the magazine. This lengthwise rocking movement of the flat surface 12^c is effected by mounting the part carrying the said flat surface 12^c upon a pivot, or pin, 13^c, which passes through the lug 90 14^c on the part 62^c which carries and operates the said flat surface 12^c and also through eyes 15^c and 16^c on a bridge-piece 17^c to which the flat surface 12^c is secured; this bridge-piece embracing the lug 14^c on the 95 carrier 62^c through which the pin 13^c passes. This bridge-piece 17^c is provided with cross-arms 18^c to act as stops, which may, or may not, be provided with adjusting means, such, for instance, as regulating screws. 100

105 In order to prevent injury to the packages to which the paper bands are to be applied, as the said packages are ejected, by the end plunger, from the feeding trough into the fixed trough, preparatory to being received by the device which carries them forward and places them on the paper band, the mechanism shown in Figs. 56 and 57 is used, in which the obstacles 30^c, hereinbefore referred to by the numeral 30, as constituting the end of the feeding trough, is made so that the surface of the said obstacle 30^c mounted on the shaft 60^c against which surface the end package bears as the packages are fed forward, is slightly inward of the 110 corresponding surface 121^c shown in Fig. 57 of the fixed trough 21^c and is kept in this position during the feeding forward of the packages by means of a projection 22^c on the carriage 230^c which operates the plunger 115 24^c by which the packages are ejected. A spring 25^c, or the equivalent, moves the said obstacle 30^c clear of the foremost package during the intervals between the movements of the packages along the trough, that is 120 while the plunger 24^c is operating, this spring 25^c being allowed to act at the requisite times by reason of the aforesaid projection 22^c on the carriage of the plunger leaving the part 26^c upon which it bore to 125 130

retain the obstacle 30° in its first named position. Thus, while the obstacle serves to properly stop the end package in proper position for being passed into the fixed trough, the said package is relieved from pressure during the time that the plunger 24° acts upon it to pass it into the said fixed trough 21°.

The mechanism now to be described relates to the carrier by which the packages are taken up and transferred to the paper bands, its object being, when wrapped packages are being dealt with, to properly retain in position the folds, or tabs, of the wrapper, at the ends of the packages.

Fig. 58 shows in end elevation the mechanism by means of which the packages are taken up and transferred to the paper bands. Figs. 59 and 60 are elevations of the mechanism as viewed from opposite sides of Fig. 58, and Fig. 61 is a plan of Fig. 58.

The packages are taken up by the carrier 33°, which is so constructed and arranged that when wrapped packages are being dealt with, the folds or tabs of the wrapper at the ends of the packages are properly retained in position. For this purpose the movable platform 30°* (see Figs. 58 and 59) on which the packages are held to be received by the said carrier 33°, is provided with a device 31°, capable of being turned by gearing 131°*, or the equivalent, against the action of the spring 32°*, into such a position as to retain one end fold, or tab of the package, in proper position, the other end fold, or tab, being, at the same time kept in position by the action of the end plunger 24°. The carrier 33° is provided with tongues 32°, which, while the two end folds, or end tabs of the package are held as described, are moved into such a position that they embrace the package including the end folds, or tabs, and retain the said end folds, or tabs, in position while the carrier 33° is conveying the package to the paper band. The part 31° carried by the movable platform, 30°* and which can be turned as aforesaid, is operated at the proper time by means of a projection 330°*, on the end plunger 24°, acting on a lever, 34° geared, as at 131°* with the said part 31°, so as to turn it into proper position to hold the end fold, or tab, of the package; and the aforesaid tongues 32° are operated at the proper time by means of a spring 35° which is allowed to come into action, by reason of the descent of the plunger 37° carrying the projection 36° against which the tongues 32° abut, so that the upward movement of the plunger 37° causes the projection 36° to raise the tongues 32° clear of the end folds, or tabs, of the package, while the downward movement of the plunger 37°, allows the tongues 32° to come into position against the said end folds, or tabs, of the package. A stop 38°,

adjustable, or not, is provided to prevent the said tongues 32° from moving beyond the required position.

Figs. 62 and 63 show a modified form of receiver into which paper bands and the packages are depressed when the folding is effected. The two upper end portions of this receiver, as indicated at 40°, are splayed out and form portions 41° corresponding in width to the width of the paper bands being dealt with. These splayed out portions may be made adjustable to suit different widths of bands. Inside each of these splayed out portions 41°, 41°, is mounted the folder 42°, each carried upon the center 43° supported by the receiver 40° so that the said folders 42°, 42°, when actuated are so turned as to press the ends of the paper band against the ends of the package, the operating means for the folders, being preferably toothed segments 44°, 44°, gearing together so that the folders act synchronously.

One of the toothed segments is positively operated in one direction against the action of a spring 45° by an arm 46° on a rod 47° 90 engaging a stop 48° on a crank-arm 49°. This latter may be integral with the toothed segment which it operates, or it may be secured on one of the pins 43°. The rod 47° is pivotally connected at one end to an arm 95 50° of a bell crank lever pivoted to the frame of the machine, and is pivotally supported at the other end by a lever 51° also pivoted to the frame of the machine. The other arm 52° of the bell crank lever is operated 100 through a rod 53° connected with any suitably moving part of the machine. As the package with the paper band beneath it is moved into the receiver, the said band is properly held in position transversely by 105 the said splayed out portions, and the ends of the said paper band which lie against the aforesaid folders are turned up and pressed by the said folders against the ends of the package.

In order to insure that the paper band is kept in position sidewise during folding by the tilting part of the table, especially where such tilting part has to operate upon an end which has any considerable length, such an 115 arrangement as shown in Figs. 64 to 69 may be used. In this arrangement the formed edge 1° which comes in contact with the paper band to fold it has two side projections 2°, 2°, at a distance apart which is 120 made, or adjusted, to suit the width of the paper bands being dealt with. These projections, one at each side of the end of the paper band to be folded, act as guides to retain the said end, during folding, in 125 proper position relatively to the package.

In cases where the ends 48°, 48°, to be folded over the package are of, or about, equal length, or each end is of considerable length, instead of one being much longer 130

than the other, a tilting portion 39^d of a table is preferably employed for folding each end of the paper band by being tilted and passed over the top of the package in 5 such a way that the ends where they meet (for instance at about the middle of the length of the package) will overlap to any desired extent. Each such tilting part of the table is provided with a gripping arrangement 46^d to grip the end and release it at the requisite times.

The parts may be operated by any suitable arrangement from any suitable moving part of the machine, for example, as follows:—the arrangement at each side being similar to each other. The gripper 46^d at each side is mounted on a pivot 42^d carried by the tilting part 39^d of the table and is provided with a downwardly projecting 20 tail-piece 51^d acted upon by a spring 47^d which closes the gripper. This tail-piece 51^d is acted upon to open the gripper 46^d at the requisite times by an arm 50^d projecting from a boss 3^d which is one of a pair 25 connected by a bridge piece 4^d and mounted so that it can be turned upon a projecting pin 5^d, or shaft, a long boss 6^d carrying the levers 41^d 41^d which operate the tilting part 39^d of the table being mounted on the said 30 pin 5^d or shaft, between the aforesaid pair of bosses. The outer boss of the said pair of bosses has a lever 165^d projecting from it which is provided with a toothed segment 54^d which, by gearing with a like segment 35 on the end of a corresponding lever projecting from the outer boss of the similar arrangement at the other side, causes the grippers 46^d of each of the tilting parts 39^d of the table to be operated from the same connection which can be secured to either of the 40 said levers (one such connection being shown at 161^d Fig. 64). The tilting parts of the table are operated by one of the levers on the aforesaid long boss, one of the said 45 levers being connected in any suitable way, as for example by the rod 131^d, with the operating means, so that, at the proper times, the tilting parts of the table will be tilted and moved over the package to lay the 50 respective ends of the paper band thereon.

What I claim is:—

1. In apparatus for applying bands to packages, a stationary magazine of bands, a rocking pick-up device comprising a pick-up arm having an adhesive-carrying contact face, and a co-operating plunger moving therewith, a folding device for applying the band to the package and means for actuating said pick-up arm to lift a band from 55 the magazine by contact with its adhesive-carrying face, to convey said band to the folding device, and there to actuate the plunger to free the band from the pick-up arm, substantially as described.

65 2. In apparatus for applying bands to

packages, a band-applying device having a folding table with delivery aperture, means for placing a pasted band on said table across the delivery aperture, a rocking carrier for receiving a package and delivering 70 the same upon the band on the folding table and a plunger moving with said carrier and serving to press said package and band into the delivery aperture in the folding table.

3. In apparatus for applying bands to 75 packages, a band-applying device having a folding table with delivery aperture, means for placing a pasted band on said table across the delivery aperture, a rocking carrier for receiving a package and delivering 80 the same upon the band on the folding table and a plunger moving with said carrier and serving to press said package and band into the delivery aperture in the folding table, together with band folding arms adapted to 85 fold the ends of the band upon the package.

4. In apparatus for applying bands to 90 packages, a band-applying device having a folding table with delivery aperture, means for placing a pasted band on said table across the delivery aperture, a rocking carrier for receiving a package and delivering 95 the same upon the band on the folding table and a plunger moving with said carrier and serving to press said package and band into the delivery aperture in the folding table, together with band folding arms adapted to fold the ends of the band upon the package, and means for maintaining the band 100 taut during the folding operation.

5. In apparatus for applying bands to 105 packages, a band-applying device having a folding table with delivery aperture, means for placing a pasted band on said table across the delivery aperture, a rocking carrier for receiving a package and delivering 110 the same upon the band on the folding table and a plunger moving with said carrier and serving to press said package and band into the delivery aperture in the folding table, together with band folding arms lying substantially in the plane of the table before the application of the band and means for moving said arms to fold the band over the package.

6. In apparatus for applying bands to 115 packages, a folding table with delivery aperture, a pair of band-folding arms lying one on each side of said aperture, one of said arms carrying a gripping device for holding the band taut during folding, substantially as described.

7. In apparatus for applying bands to 120 packages, a folding table with delivery aperture, a pair of band-folding arms lying one on each side of the aperture, means for delivering a package upon a band placed across the delivery aperture of the folding table and means for imparting both vertical and horizontal motion to one of said 125 130

folding arms to fold the band against the sides and over the top of the package as it enters the delivery aperture.

8. In apparatus for applying bands to packages, a folding table with delivery aperture, a pair of band-folding arms lying one on each side of said aperture, means for delivering a package upon a band stretched across said delivery aperture in the folding table and means for synchronously pushing the package through said aperture and actuating said folding arms to fold the ends of the band over the sides and top of said package, substantially as described.

15 9. In apparatus for applying bands to packages, a band-folding arm, and a band-gripping device carried thereby, said arm being recessed to carry the gripper out of contact with the surface of the package during the folding operation, substantially as described.

10. In apparatus for applying bands to packages, a folding table with discharge aperture, a passage leading from the latter, 25 one wall of said passage being spring-pressed to confine the banded packages temporarily therein, together with cam means for moving said wall outward against the action of its spring to permit the free passage of the packages therethrough at predetermined intervals, substantially as described.

11. In apparatus for applying bands to packages, a movable platform, a carrier co-operating therewith, a pair of jaws on the carrier, the jaw first in the direction of movement of the platform being hinged and a three arm lever for operating the jaw under the action of a spring in one direction and a projection on the movable platform in the other direction, substantially as described.

12. In apparatus for applying bands to packages, a folding table with delivery aperture, a receiving passage beneath said aperture, a plunger for pressing the packages into said passage, a supporting lever forming the bottom of said passage and means for synchronously pressing said plunger and lever toward each other to compress the packages in the passage, substantially as described.

13. In apparatus for applying bands to packages, a folding table with delivery aperture, a receiving passage beneath said aperture, a plunger for pressing the packages into said passage, a supporting lever forming the bottom of said passage and means for synchronously pressing said plunger and lever toward each other to compress the packages in the passage, together with means for moving away the supporting lever in advance of the plunger, for the purpose described.

14. In apparatus for applying bands to packages, a folding table with delivery aperture, a receiving passage beneath said aperture, a plunger for pressing the packages into said passage, a supporting lever forming the bottom of said passage and means for synchronously pressing said plunger and lever toward each other to compress the packages in the passage, together with means for moving away the supporting lever in advance of the plunger, and means for forcing out the package adjacent said supporting lever after the latter has been retracted.

15. In apparatus for applying bands to packages, a rocking pick-up device, having a pivoted arm with adhesive-receiving surface, an adhesive applier therefor and a rocker arm carrying said applier, together with cam means for rocking said applier to maintain the same in contact with the receiving surface of the pick-up arm, for the purpose described.

16. In apparatus for applying bands to packages, a rocking pick-up device with adhesive-receiving surface, an adhesive applier therefor, a rocker arm carrying the latter and means for adjusting said rocker arm, together with cam means for rocking said applier to maintain the same in contact with the receiving surface of the pick-up device, for the purpose described.

17. In apparatus for applying bands to packages, a pick-up device, comprising a rocker arm, a carrier bracket thereon and a pick-up shoe transversely pivoted thereon to permit lengthwise oscillation thereof, substantially as described.

18. In apparatus for applying bands to packages, a pick-up device, comprising a rocker arm, a carrier bracket thereon and a pick-up shoe transversely pivoted thereon to permit lengthwise oscillation thereof, together with a stop device for limiting the oscillation of the pick-up shoe or the bracket.

19. In apparatus for applying bands to packages, a package feed trough, a stationary receiving trough, a detent at the discharge end of the feed trough and means for moving the latter out of engaging position during the feed of a package to the receiving trough, substantially as described.

20. In apparatus for applying bands to packages, a rocking carrier for transferring the package from its delivery trough to the folding table, grippers on said carrier for holding the package during transit and retaining fingers pivoted on said carrier for holding in position the end flaps of the package wrapper during transit, together with means for moving said grippers and retaining fingers into and out of engagement with the package, substantially as described.

21. In apparatus for applying bands to packages, a folding table with discharge aperture, means for placing a band with wet adhesive over said discharge aperture, means for placing a package upon said band above the discharge aperture, means for pressing said package into the discharge aperture, and means for folding the band over said package, said folding means including a tilting arm and means for rocking the same over the package to fold and apply the band to the upper surface of the package, substantially as described.
22. In apparatus for applying bands to packages, a folding table with discharge aperture, means for placing a band with wet adhesive over said discharge aperture, means for placing a package upon said band above the discharge aperture, means for pressing said package into the discharge aperture, and means for folding the band over said package, said folding means including a tilting arm and means for rocking the same over the package to fold and apply the band to the upper surface of the package, together with means for laterally guid-

ing the band during folding, substantially as described.

23. In apparatus for applying bands to packages, a folding table with discharge aperture, means for placing a band with wet adhesive over said discharge aperture, means for placing a package upon said band above the discharge aperture, means for pressing said package into the discharge aperture, and means for folding the band over said package, said folding means including two tilting arms one on each side of the discharge aperture, gripping means carried thereby for holding opposite ends of the band and means for tilting said arms to fold the ends of the bands over and apply the same to the package, substantially as described.

In testimony whereof I have signed my name to this specification in the presence of two subscribing witnesses.

WILLIAM ROSE.

Witnesses:

GILBERT FLETCHER TYSON,
EDWARD GEORGE DAVIES.
